UNITED STATES PATENT OFFICE.

ORA E. MITCHELL, OF LOS ANGELES, CALIFORNIA.

DIRIGIBLE HEADLIGHT.

No. 866,502.

Specification of Letters Patent.

Patented Sept. 17, 1907.

Application filed April 26, 1906. Serial No. 313,744.

To all whom it may concern:

Be it known that I, ORA E. MITCHELL, a citizen of the United States, residing at Los Angeles, in the county of Los Angeles and State of California, have invented a new and useful Dirigible Headlight, of which the following is a specification.

This invention relates to dirigible headlights for vehicles, and has particular reference to means for controlling the projecting rays issuing from a headlight.

10 The main object of this invention is to provide a vehicle headlight which may be turned to throw its light in either a straight or a lateral line, as may be desired, and is especially adaptable for use in connection with railway cars, launches, boats, automobiles, and other 15 motive-power vehicles.

Another object of this invention is to provide means for accomplishing these ends, which are devoid of the usual cumbersome parts, and which are easily assembled and placed together, while at the same time preserving its durability, practicality, and simplicity.

20 With these and other objects in view, the invention consists in the features, details of construction, and combinations of parts, as will be described in connection with the accompanying drawings, and then be 25 more particularly pointed out in the claims.

In the drawings, Figure 1 shows a rear end elevation of a headlight supported in its bifurcation, the controlling means being shown in section. Fig. 2 is a vertical section through a fragment of one of the supporting arms for the headlight, the cup and a fragment of the lamp, the interior of said cup being shown in full lines except the member 13'. Fig. 3 is a top plan view with the cover removed. Fig. 4 is a detail of the stem which is arranged to be fastened to the lamp proper.

30 Referring more in detail to the drawing, 1 represents a headlight proper, provided with trunnions 2, which trunnions are carried by a prong or bifurcation 3. The headlight, as will be seen, is so mounted as to be pivotally inclined in either one direction or the other, and

40 the stem 4 of the bifurcation is seated in a socket 5 provided in the cup 6, which, in turn, is mounted upon a bracket 7 or upon the dash-board of the vehicle. Said socket 5 has a tubular sleeve 5' having a rectangular opening and forming a socket for the reception of the

45 stem 4. The sleeve is made integral with a short lever or arm 8, which lever extends to the edge of the annular cup 6. Coiled around said tubular sleeve 5' is a spring 9 having its respective ends 10 and 11 extending away from the body portion of the convolute, and bent 50 upon itself at substantially right angles and forming tangs. These tangs extend vertically with respect to the cup 6 and are arranged to impinge against the arm 8 on either side thereof, the tendency of the spring being to force said tangs toward one another. From the arrangement as shown, it is obvious that by moving the arm 8 either to the right or to the left, it will carry with it one

tang of said spring 9, and vice versa when the arm is forced in the other direction, the tendency always being to bring said arm in a straight-ahead position. Now in order to maintain one tang of said spring in its normal 60 position while the other is being moved against its tension by the arm 8, I provide a block 12 which is located intermediate the tangs, which block is screwed or otherwise secured in the cup 6. Thus, as the arm is moved towards the right, the left tang will remain stationary while the tension of the right tang is being exerted, and vice versa.

The arm 8 provided in the cup is arranged to travel about a quarter of the circumference of the cup in either direction, and in order to keep the respective tangs in 70 position when they are carried around to this quarter position by the movement of the arm 8, I provide an elliptically-shaped body or member 13 upon which the arms of the coil spring 9 are designed to rest.

The stem of the bifurcation 3, as is obvious, is intended to extend into the socket 5 formed in the tubular sleeve 5'. Now as the headlight, pivotally supported in said bifurcation, is turned either to the right or to the left, the tension of the spring is exerted, and manipulation by hand, in order to bring said headlight 75 back into its normal position,—which is straight ahead,—is obviated, the spring itself carrying with it the arm 9 performing this function.

A cover 14 is arranged to fit on the cup 6, the said cover having a conical extension 15 made integral with 85 said cover 14. Said conical extension has likewise a rectangular opening corresponding to that of the socket, and is arranged to allow the stem 4 of the bifurcation to pass therethrough. Through the periphery of said cone or conical projection 15 extends a thumb-screw 14', 90 which is arranged to engage said stem 4 of the bifurcation 3, and if any desired position other than the normal position of the headlight is desired, to clamp it against movement from that position.

A cup 6' similar to cup 6 is arranged to be secured to 95 one arm of the bifurcation 3 in a vertical position. It is provided with a tubular sleeve 52 having a rectangular bore 53, which sleeve is loose in said cup 6'. Said sleeve 52 is provided with an integral arm 81 and extends vertically downward in said cup 6'. To the side 100 of said arm 81 is a helical spring 91 coiled about the tubular sleeve 52, the respective ends of said spring extending away from the body portion of the convolute and bent upon themselves at right angles, as seen at 10' and 11'. Said ends are held spaced by a block 12 105 against which they bear. When the headlight is tilted either upwardly or downwardly, the arm 81 engages either of the spring ends 10' and 11' and carries with it one or the other of said ends against the tension of the helix 91, and according to the direction of movement 110 of the headlight. The release of the headlight 1 causes the automatic return of the same to its normal position.

13' is an elliptical member interposed between said arm and block and serves to guide said arm as well as to prevent the dislocation of the spring ends 10' and 11'. 41 5 52 and arranged to engage the conically-shaped body 18 which is secured to the body proper of the lamp or head-light by rivets 19. A thumb-screw 17 may likewise be provided on the other arm of the bifurcation to engage the trunnion carried by said lamp. From the above 10 description it is obvious that the control of the head-light proper, in a plane vertical to its axis, is absolutely independent of the control of its support; and likewise the control of the support in a plane perpendicular to its axis independent of that of the headlight.

15 The thumb-screw 14 extends through the walls of said conical piece and engages one wall of the rectangular stem 4, which prevents the lamp from turning on its pivot points, and which is further designed to level the lamp in case the jar from the vehicle carrying the same 20 25 has forced it out of a straight line; consequently causing the light, provided it be an arc light, to fade or perhaps to extinguish.

It is, of course, understood that the lamp as represented and described in connection with its support, is not limited to any particular kind of lamp; that is to say, the means for producing the light is not limited to acetylene, gas, or electricity, all of which may be used in connection with my arrangement.

What I claim and desire to secure by Letters Patent of the United States is:—

1. The combination with a support and means for pivotally mounting said support comprising a cup, a tubular sleeve in said cup provided with a rectangular bore arranged to receive the stem of the support, a spring coiled about said tubular sleeve and having its ends terminating in tangs extending at right angles to the body of the spring, a block for keeping said tangs spaced, a lever integrally united with said sleeve and extending between said tangs, an elliptical member interposed between said lever and block for guiding said lever, and means for securing said support in its adjusted position. 30 35 40

2. The combination with a support and means for pivotally mounting said support, comprising a cup, a tubular sleeve in said cup provided with a rectangular bore arranged to receive the stem of the support, a spring coiled about said tubular sleeve and having its ends terminating in tangs extending at right angles to the body of the spring, a block for keeping said tangs spaced, a lever integrally united with said sleeve and extending between said tangs, an elliptical member interposed between said lever and block for guiding said lever, means for pivotally mounting a headlight in said support comprising a cup secured in one arm of said support, having spring-actuated means for governing the movement of the headlight, and means for securing said headlight in its adjusted position. 45 50 55

In testimony whereof, I have hereunto set my hand at Los Angeles, California this 17th day of April 1906.

ORA E. MITCHELL.

In presence of—

ANTON GLOETZNER, Jr.,
JULIA TOWNSEND.
